UNITED STATES PATENT OFFICE.

JAMES WILLIAM RAIRDEN, OF CHATTANOOGA, TENNESSEE.

AIRSHIP.

1,290,348.

Specification of Letters Patent.

Patented Jan. 7, 1919.

Application filed March 30, 1918. Serial No. 225,800.

To all whom it may concern:

Be it known that I, JAMES W. RAIRDEN, a citizen of the United States, residing at Chattanooga, in the county of Hamilton and 5 State of Tennessee, have invented new and useful Improvements in Airships, of which the following is a specification.

This invention relates to airships of the lighter than air type, the object in view 10 being to produce a machine of the class referred to capable of sustaining itself for a long period of time in the air and capable of attaining great altitudes.

A further object of the invention is to produce a machine of the character referred to 15 which embodies in connection with an aerostat and a car suspended below the same, means for producing gas with which to fill the aerostat, and means for exhausting air 20 from the aerostat preparatory to introducing gas therein, the gas producer, the engine, and the vacuum pump being located and housed within the car.

A further object of the invention is to provide 25 convenient means for exhausting the gas from the aerostat to enable the machine to descend and make a safe landing.

With the above and other objects in view, the invention consists in the novel construction, combination and arrangement of parts, 30 herein described, illustrated and claimed.

In the accompanying drawings:—

Figure 1 is a view partly in side elevation and partly in section of the improved airship.

35 Fig. 2 is a front elevation thereof.

Fig. 3 is a rear elevation of the same.

Fig. 4 is a plan view of the machine.

Fig. 5 is a horizontal section thereof.

Referring to the drawings 1 designates 40 an aerostat of elongated cylindrical formation with tapering or pointed end portions enabling the same to be driven through the air with minimum head resistance. The aerostat 1 is divided by partitions into compartments 2, 3, 4, 5, 6, 7 and 8, more or less compartments being used according to the size of the aerostat and the machine. The shell of the aerostat is preferably formed of tempered sheet metal, preferably copper and 45 may be internally braced in any suitable way to prevent the same from collapsing when a partial vacuum is created therein preparatory to introducing the gas. Suspended below the aerostat 1 is a car or gondola 9 preferably in the form of a boat having tapered or pointed front and rear end

portions as shown. The car 9 is connected with and suspended from the aerostat by means of metal straps 10 of any suitable number. Mounted within the car and on the floor 11 thereof are engines 12 of any suitable type and connected to and driven by the engine is a vacuum pump 13 from which lead pipes 14 which extend from the car upwardly within the aerostat where they 60 are provided with branches 15 leading to the several airtight compartments of the aerostat as shown in Fig. 1. This enables each of the compartments of the aerostat to be filled with its own supply of gas so that 65 in case of a puncture occurring in one of the compartments, the other compartments will not be affected. The pipes 14 are provided with stop cocks or valves 16 enabling the same to be opened and closed by the operator. 17 designates a gas producer from which pipes 18 lead to and communicate with the pipes 20, the pipes 18 being adapted to be opened and closed by valves or stop cocks 19. The exhaust pipes 19' lead from the 70 pipes 18 upwardly through one of the compartments of the aerostat and are adapted to exhaust above said aerostat as indicated in Fig. 1. The pipes 19' are controlled by valves or stop cocks 20. 21 designates a 75 fuel tank which communicates with the carburetor of the engine 12, the fuel tank being located within the boat-like body or car 9.

Located at opposite sides of the aerostat are box-like planes 22 having a plurality of 80 superposed planes closed in by the side walls 23. The planes 22 are both mounted upon a central shaft 24 extending transversely of and beneath the aerostat and mounted in 85 bearings 25 secured to the aerostat. The 90 housing of the shaft 24 is braced by diagonal stays 26 attached at one end to the car 9 and at the other end to the aerostat. Flexible 95 connections 27, such as cables are secured at their upper ends to the planes or horizontal 100 rudders 22 and extend downwardly into the car where they pass around guide pulleys 28 and thence upwardly around the hub of a controlling wheel 29 by means of which the operator may tilt the planes 22 at any desired angle for rising to a higher altitude or 105 descending to a lower altitude.

At the rear of the machine I arrange a vertical rudder post 30 having at the bottom thereof a cross head or tiller 31 and also 110 having at a higher elevation just below the aerostat another cross bar or tiller 32. A

lower vertical rudder 33 extends backwardly from and is fixedly secured to the rudder post 30. An upper vertical rudder 34 extends rearwardly from another rudder post 35 having a cross arm or tiller 36 from which connections 37 extend to the upper tiller 32 of the rudder post 30. From the lower tiller 31, flexible connections 38 extend lengthwise of the car around guide pulleys 39 and around the hub of another controlling wheel 40 by means of which the craft may be steered to one side or the other. The controlling wheels 29 and 40 are arranged close together and conveniently for the operator who may thus control the directional movement of the craft.

At the front and rear of the machine I mount two propellers 41 the shafts 42 of which extend into and longitudinally of the car where they are geared to the shafts of the engines 12 in connection with which I employ a clutch 43 which may be operated by a lever 44 for the purpose of throwing the propellers into and out of operation as may be required without stopping the engine.

In order to operate the craft, the engine is started and the valves 16 are opened, the valves 19 and 20 remaining closed. This causes the pump 13 to exhaust the air from the aerostat 1. As soon as this has been effected, the valves 16 are closed and the valves 19 are opened permitting the gas generated by the producer 17 to flow through

the pipes 14 and fill the compartments of the aerostat. When it is desired to descend, the valves 19 are closed and the valves 16 and 20 opened. Thereupon the engine 12 operates to exhaust the gas to any desired degree from the aerostat and discharge the same through the exhaust pipes 19.

The machine may of course be made of any size according to the load to be carried and the car may be made of suitable size to carry safely any desired number of passengers. The craft may be used as a pleasure craft or for commercial uses or war purposes and will be safe at any altitude.

I claim:—

In an airship, the combination of an aerostat, a car suspended below the aerostat, crossed stays connecting said aerostat and car and having bearings at their crossing points, a normally horizontal shaft passing through said bearings, a vertical rudder, horizontal rudders in the form of box planes 55 centrally mounted on said shaft and extending throughout the greater portion of the length of the aerostat, an operating wheel for said horizontal rudders located in the car, and flexible connections controlled by 60 said wheel and extending upwardly to the horizontal rudders adjacent to the front and rear ends of the latter.

In testimony whereof I affix my signature.

JAMES WILLIAM RAIRDEN.
